UNITED STATES PATENT OFFICE.

DAVID J. NEVILL, OF DENVER, COLORADO, ASSIGNOR TO JOHN VAN NOSTRAND DORR,
OF LEAD, SOUTH DAKOTA.

ORE CONVEYER AND CLASSIFIER.

1,024,647.

Specification of Letters Patent. Patented Apr. 30, 1912.

Application filed November 5, 1908. Serial No. 461,211.

To all whom it may concern:

Be it known that I, DAVID J. NEVILL, who was formerly a subject of Great Britain and have taken out my first papers for citizenship in the United States, residing at Denver, in the county of Denver and State of Colorado, have invented certain new and useful Improvements in Ore Conveyers and Classifiers; and I do hereby declare the following to be a full, clear, and exact description of the invention, such as will enable others skilled in the art to which it appertains to make and use the same.

This invention relates to ore conveyers and classifiers, and especially to mechanical movements for actuating the rakers of the ore conveyers and classifiers.

An object of the present invention is to provide an ore conveyer and classifier having a raker or rakers therein which may be operated at different levels.

A further object of the invention is to provide in an ore conveyer and classifier a raker or rakers, the different ends of which may be independently raised or lowered relative to the bed.

A further object of the invention is to provide in an ore conveyer and classifier improved mechanism imparting a new and desirable motion to the rakers.

With these and other objects in view, the invention comprises certain novel constructions, combinations and arrangements of parts, as will be hereinafter fully described and claimed.

In the drawings:—Figure 1 is a perspective view of the improved ore conveyer and classifier. Fig. 2 is a view of the conveyer and classifier in side elevation with the side walls of the body removed showing the rakers in side elevation. Fig. 3 is a top plan view of the ore conveyer and classifier. Fig. 4 is a view of the operating mechanism at the upper end of the conveyer and classifier. Fig. 5 is a transverse view of the rakers and operating mechanism.

Like characters of reference designate corresponding parts throughout the several views.

The improved ore conveyer and classifier forming the subject-matter of this application comprises a settling trough having a bed 10, side walls 11, and a low central partition 12, dividing the body into two longitudinal compartments separated by the low

partition and such body supported at an inclination in any approved manner as by the base 13. Upon the base or body are erected uprights 14 and 15 carrying at their upper ends shafts 16 and 17, respectively, 60 upon which said shafts are respectively pivoted bell crank levers 18 and 19.

From the horizontally extending arms of the bell crank levers 18 and 19 depend links or hangers 20 and 21 carrying at their lower 65 ends universal joints 22 and 23, respectively, connected pivotally with supports 24 and 25. At their lower extremities or bases the supports 24 and 25 are connected with longitudinally extending frame pieces 26 forming the main frame of the rakes which said frame pieces 26 are connected by laterally extending cross-pieces 27, the frame pieces 26 being preferably constructed of channel iron, while the cross-pieces 27 are preferably 75 constructed of angle iron, as shown particularly in Fig. 2.

Connecting the upper extremity of the bell crank levers 18 and 19 is a rod comprising the sections 28 and 29 connected by 80 a turn buckle 30 whereby both of the bell crank levers will be operated in unison, but the angle of such bell crank levers relative to each other may be changed by manipulating the turn buckle 30, and shortening or 85 lengthening the rod composed of the sections 28 and 29.

At the end of the body uprights 31 and 32 are erected, and a power shaft 33 journaled thereon carrying any approved means 90 for applying power thereto as the belt pulley 34, and with a pinion 35 rigidly carried on said shaft 33, and intergeared with a gear 36 carried rigidly upon a shaft 37 similarly journaled upon the uprights 32. Upon 95 opposite sides of the uprights 32 the shaft 37 carries cams 38 and 39, respectively. Pivoted upon the uprights 31 and 32 are also levers 40 and 41 having at their lower ends rollers 42 and 43, bearing upon the 100 peripheries of the cams 38 and 39. At their upper ends the levers 40 and 41 are bifurcated as indicated at 44 producing thereby a bearing slot in which are pivotally mounted cross-heads or pins 45 and 46, carried by 105 sleeves 47 and 48, respectively, through which said sleeves extend rods 49 and 50, respectively. The rods 49 and 50 are screw-threaded as at 51 and inserted through yokes or stirrups 52 and 53, whereby a rotation of 110

the rods 49 and 50 will vary the distance between the sleeves 47 and 48, and the yokes 52 and 53, and such rotation of the rods 49 and 50 is accomplished in any approved manner, as by the cranks 54 and 54'. Upon the shaft 37 are also mounted crank arms 55 and 56 having, respectively, wrist pins 57 and 58, upon which are journaled the ends of pitman rods 59, extending to and pivoted upon the supports 24 as indicated in dotted lines at 60.

The usual means, as the trough 61, is provided for feeding material to the device with discharge pipes or orifices 62 and 63, for discharging the washings, sand, slime, etc., from the machine.

In operation the water, sand and slime is admitted to the settling trough through the feed trough 61 in the usual way and stands at the level indicated by the dotted line in Fig. 2. The solid material settles to the bottom of the trough while the liquid and slime flows over into the discharge trough 62. The trough may, when desired, be drained through a discharge opening 63. The rake mechanism is set in motion by rotating the drive shaft, 33 which transmits motion to the shaft 37, thus rotating the cams 38 and 39 to give an irregular motion to the levers 40 and 41. By reason of the rods 49 and 50 connecting the levers with the bell crank levers 18 and the rods connecting the bell crank levers, the motion transmitted from the cams results in a substantially vertical movement of the horizontal extremities of the bell crank levers 18 and 19, which motion is transmitted through the links or hangers 20 and 21 to the supports 24 and 25, and carrying therewith the rakes. At the same time the entire rake structure is given a longitudinal motion by the rotation of the crank arms 55 and 56, which motion is transmitted through the pitmen 59. It will thus be seen that the cams furnish an irregular up and down reciprocating motion to the rakes while the crank arms transmit a regular longitudinal reciprocating motion to the rake, the resultant motion being that the rakers are drawn toward the front of the machine, while down, and moved rearwardly of the machine, while raised. The solid material is thus moved by the rakes to the discharge end of the machine while the slimes and other liquid material flow over into the discharge trough 62. The trough may be at any time drained through the discharge opening 63.

The means for regulating the position of the rakes is very important, it being understood that when the machine has stopped for a length of time, the sands and material become packed down and are operated with considerable difficulty, and in such condi-

tion the crank arms 53 and 54 are manipulated to raise the entire rake sufficiently to permit operation and to rake off only part of the settled material. As the machine continues to operate the rakes are lowered by the reverse manipulation of the crank arms 53 and 54 until in normal working position.

At times it is desirable to work the rakes with the opposite ends at a different height above the bed of the machine and this is accomplished by manipulating the turn buckle 30 increasing or decreasing the length of the connecting rod whereby when the rod is shortened the lower end of the rake is raised and when lengthened the lower end is lowered. Taken in conjunction with the manipulation of the crank arms 53 and 54, the rakes may be given any necessary operative relation to the bed of the machine.

What I claim is:—

1. An ore conveyer and classifier, comprising a settling trough, a rake mounted to reciprocate therein, bell crank levers, means for operating them, and links or hangers connecting the bell crank levers with the rakes and which have universal joints therewith.

2. In an ore conveyer and classifier, the combination of a settling trough, a rake mounted to reciprocate therein, bell-crank levers mounted at opposite ends of the trough, jointed connections between the rake and the levers, a rod connecting the bell-crank levers, an operating lever, a rod connecting this lever with the bell-crank lever at the delivery end of the apparatus, and means for adjusting the length of the rod whereby both bell-crank levers may be moved simultaneously to raise the rake in the trough and to thus adjust its position therein.

3. In an ore conveyer and classifier, the combination of a settling trough, a rake mounted to reciprocate therein, bell crank levers mounted at opposite ends of the trough, jointed connections between the rake and the levers, a rod connecting the bell crank levers, devices for adjusting the length of the rod, an operating lever, a rod connecting this lever with the bell crank lever at the delivery end of the apparatus, and means for adjusting the length of the rod whereby both bell crank levers may be moved simultaneously to raise the rake in the trough and to thus adjust its position therein.

In testimony whereof I have affixed my signature in presence of two witnesses.

DAVID J. NEVILL.
